CLAIM

The ornamental design for a modular shoe organizer or
similar article, as shown and described.

DESCRIPTION

FIG. 1 is a top plan view of a modular shoe organizer or
similar article showing my new design;

FIG. 2 is a rear elevational view thereof;

FIG. 3 is a front elevational view thereof;

FIG. 4 is a right side elevational view as seen when in
use, the left side being a mirror image thereof;

FIG. 5 is a bottom plan view thereof; and

FIG. 6 is a perspective view thereof.

FIG. 1

FIG. 5

FIG. 3

FIG. 4

FIG. 2

FIG. 6
